[57] CLAIM

The ornamental design for device for removing caps or lids from sealed containers, as shown and described.

DESCRIPTION

FIG. 1 is a front perspective view of a device for removing caps or lids from sealed containers showing our new design;

FIG. 2 is a rear perspective view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a top plan view thereof;

FIG. 8 is a bottom plan view thereof;

FIG. 9 is a front perspective view of a second embodiment of that shown in FIG. 1;

FIG. 10 is a rear perspective view of that shown in FIG. 9;

FIG. 11 is a front perspective view of a third embodiment of that shown in FIG. 1; and

FIG. 12 is a rear perspective view of that shown in FIG. 11.
